US0D1048818S

(12) **United States Design Patent** (10) **Patent No.:** **US D1,048,818 S**
(45) **Date of Patent:** **** Oct. 29, 2024**

(54) **DRINKING GLASS**

(71) Applicant: **Fiskars UK Limited**, Stoke-On-Trent (GB)

(72) Inventors: **Matthew Kehoe**, Waterford (IE); **Lee Critchlow**, Stoke-On-Trent (GB)

(73) Assignee: **Fiskars UK Limited**, Stoke-On-Trent (GB)

(**) Term: **15 Years**

(21) Appl. No.: **35/516,968**

(22) Filed: **Mar. 14, 2023**

(80) **Hague Agreement Data**

Int. Filing Date: **Mar. 14, 2023**

Int. Reg. No.: **DM/228173**

Int. Reg. Date: **Mar. 14, 2023**

Int. Reg. Pub. Date: **Apr. 28, 2023**

(51) **LOC (14) Cl.** **07-01**

(52) **U.S. Cl.**

USPC **D7/525**; D7/524

(58) **Field of Classification Search**

(57) **CLAIM**

The ornamental design for a drinking glass as shown and described.

DESCRIPTION

1. Drinking glass
- 1.1 :Perspective
- 1.2 :Front
- 1.3 :Back
- 1.4 :Left
- 1.5 :Right
- 1.6 :Top
- 1.7 :Bottom

The characteristic features of each design lie in the combination of the shape and pattern; the grey areas are shown for illustrating sand blown areas of the glass of each article.

1 Claim, 7 Drawing Sheets
